(57) **CLAIM**

The ornamental design for a side-laced dress, as shown and described.

DESCRIPTION

FIG. 1 is a front view of a side-laced dress showing my new design in its environmental use;

FIG. 2 is a back view thereof, shown in its environmental use;

FIG. 3 is a left side view thereof, shown in its environmental use;

FIG. 4 is a right side view thereof, shown in its environmental use; and,

FIG. 5 is a detailed side view thereof, showing the leather and laces.

My side-laced dress is characterized by a versatile fabric dress for women that can be laced and adjusted for size and body shape with the leather-seamed lacing design on both sides. Broken lines in drawings represent environmental structure and inform no part of the claimed design.
